UNITED STATES PATENT OFFICE.

JOSEPH C. DAY, OF PHILADELPHIA, PENNSYLVANIA, ASSIGNOR TO BAKER,
PRATT & CO., OF NEW YORK, N. Y.

DESIGN FOR A SETTEE-FRAME.

SPECIFICATION forming part of Design No. 15,712, dated January 13, 1885.

Application filed October 14, 1884. Term of patent 7 years.

To all whom it may concern:

Be it known that I, JOSEPH C. DAY, residing in the city and county of Philadelphia, State of Pennsylvania, have invented and produced a new and original Design for Settee-Frames, of which the following is a specification, reference being had to the accompanying photographic illustration, forming part thereof.

10 The leading features of my design for a settee-frame are the ornamentalations, first, of the seat-support, and, next, the legs.

15 A represents the side portion of a settee-frame, of which *a* is the seat-support, *b* the back, and *c c* the legs, and *d d'* the connecting cross-bars of the legs. Between the seat-support *a* and top cross-bar, *d*, are arches *e e'*, the

central arch, *e'*, being of less width than the arches *e*. Between the cross-bars *d d'* is a quarterfoil, *f*, from the sides of which radiate 20 spear-heads *g*, the latter joining, respectively, the cross-bars *d d'* and legs *c c*. At the center of the quarterfoil *f* is an open cross, *h*.

I claim—

25 A design for a settee-frame, having a cross-bar, *d*, legs *c*, quarterfoil *f*, an open cross, *h*, within the quarterfoil, a cross-bar, *d'*, and pieces *g*, radiating from the quarterfoil and joining the cross-bars *d d'* and legs *c*, respectively, as shown and described.

JOS. C. DAY.
